Otto Winter, Wilhelmshaven, Germany, assignor to Olympia Werke G. m. b. H., Wilhelmshaven, Germany, a corporation of Germany

Application December 4, 1953, Serial No. 27,939

Term of patent 14 years

(Cl. D87—5)

To all whom it may concern:

Be it known that I, Otto Winter, a citizen of Germany, residing at Wilhelmshaven, Germany, have invented a new, original, and ornamental Design for a Typewriter Carrying Case, of which the following is a specification, reference being had to the accompanying drawing, forming a part hereof, and wherein:

Fig. 1 is a perspective view of a typewriter carrying case showing my new design; and

Fig. 2 is a plan view of the same.

The dominant features of the design reside in the portions shown in full lines.

I claim:

The ornamental design for a typewriter carrying case, as shown and described.
